AUGUSTUS JESSE BOWIE, OF SAN FRANCISCO, CALIFORNIA

ELECTRIC SWITCH

Application filed January 28, 1925. Serial No. 4,825.

It is the object of this invention to provide improvements in the operation of switch blades and switch clips. The invention is particularly applicable to outdoor practice 5 where after periods of long disuse the blade is subjected to corrosion and sticking in the switch clips. This sticking is so severe in some cases that the operation of long blades is impracticable without auxiliary means of 10 freeing the blades from the clips.

One of the methods by which I overcome the difficulties is to mount the clip on a movable carriage and to have the initial motion of the clip give a small torsional movement 15 of the blade within the clip, thus tending to free the blade from any sticking.

The most important part of the invention consists in the fact that the clip contacts are positively pulled apart from the blade by the 20 initial motion of the mechanism to operate the blade. This result may be accomplished in many ways, such as imparting pressure to the clip faces from the initial movement of the clip and blade in such a manner as to pull 25 the clip faces definitely away from the blade and thus directly break any frictional hold. This is a most effective way of overcoming the effect of any corrosion or freezing in cold climates.

30 As an alternative, however, the blade itself may be accordingly pulled away from the clip; for instance, if the blades surround the clip contact they may be separated by suitable wedging action, or, if the blades are 35 double and make external contact with the clip they may be drawn together by a corresponding action. An important feature is that blade and clip must be so correlated as preferably to have an initial movement before 40 engaging with the means which is used to separate the contact of these two parts. While the initial motion may be such as to cause a twisting between the blade and clip, it is generally preferable, however, to make 45 the clip jaws of such construction that if the pull between the blade and clip jaws is sufficiently hard, the jaws of themselves will stick with the blade until they impinge upon the means provided for freeing the blade and 50 clip jaws.

Another important feature of the invention is that the initial motion allowed will be such that a reasonable amount of inertia can be obtained so as to give a hammer blow for the liberating of the blade from the clip. 55

Fig. 1 shows a side elevation of a switch.

Fig. 2 shows an enlarged corresponding elevation of the clip contact of said switch.

Fig. 3 shows a longitudinal section of Fig. 2. 60

Fig. 4 shows a transverse section and elevation of Fig. 2, along the line A, A. In these figures the blade makes contact between two clip faces.

Fig. 5 shows in plan view an alternative 65 construction wherein the clip consists of a central member with a bifurcated blade surrounding the same.

Fig. 6 shows a side elevation thereof.

Fig. 7 shows a sectional view of Fig. 5, on 70 the line B, B.

Fig. 8 shows a sectional view of Fig. 6, on the line C, C.

Fig. 9 shows a plan view of another type 75 of construction similar to that shown in Fig. 1.

Fig. 10 shows a side elevation of same.

Fig. 11 shows a section on the line D, D, of Fig. 10.

Fig. 12 shows a section along the line E, E, 80 of Fig. 10.

Fig. 13 shows a modified form of construction wherein the blade structure has a pivoted end to engage with the clip.

Fig. 14 shows a cross sectional elevation of 85 Fig. 13, along the line F, F.

1, 1, are clip faces mounted in a U shaped spring clip 2, which forces the faces into contact with the clip by pressing the ball shaped surfaces 23. 3, is a flexible shunt attached 90 to clip faces 1, 1, for conveying current to the bar 4, from which the current is taken thru the lug 5, to the outgoing circuit. 6, is a metal casing carrying the clip consisting of clip faces 1, spring 2, and shunt 3 and lug 95 rigidly attached thereto, and is pivoted on pivot 7, which is supported in upright 8, rigidly attached to clip base 9, mounted on clip insulator 10. 11, is a U shaped piece 100 mounted on base 9, with its sides surrounding

the clip and terminating in bent ends 12, 12, which are above the clip faces. 13, is a blade pivoted on pivot 14, mounted on hinge insulator 15. 16, is an arm of the blade 13. 17, is an operating link thru which the blade is moved by any suitable mechanism, such as the rocking insulator 18, mounted on shaft 19, in bushing 20, rotating in support 21. 22, 22, are terminal lugs on clip faces 1, 1, which limit the angular motion of clip faces in U shaped spring 2. The clip faces are provided with ball joints 23, and round pins 24, which latter extend thru holes in the spring clip 2. The mounting hence is such that a small rotation of clip faces 1, 1, is allowable in spring 2, but the bosses 22, 22, impinging against the upper part of spring 2 will limit the angle of rotation.

The action is as follows:
20 When blade 13 is operated in opening the switch thru the motion of insulator 18, and link 17, the clip faces 1, 1, and casing 6, are carried upward rotating about pivot 7.

The aforesaid mounting of clip faces allows a slight torsional angle. After the clip has moved up a sufficient distance the ends 12, 12, will strike on the clip faces 1, 1, and will positively separate these clip faces from the blade, thus overcoming the effect of adhesion between the clip faces and blade end. The fact that a short distance of travel is allowed before this result takes place provides a hammer blow which is very useful in overcoming any sticking of the clip faces on the blade and as a result the blade is readily released with comparatively small effort.

The construction shown in Figs. 1 to 4, inclusive provides for the breaking of friction hold previously mentioned and is generally ample to overcome in a simple manner the frictional resistance between the clip and blade. The initial result is that the clip faces 1, 1, after striking ends 12, 12, will pivot around the ball seats 23 and allow only the lower half of the blade edge to remain in contact with the clip faces 1, 1, until the blade is entirely withdrawn. In case it is desired to pull the entire clip faces away from the blade, this could be done by providing wedge shaped pieces on the outer end of bosses 24, which would ride upward on motion of casing 6, on corresponding fixed wedges, thus positively pulling the entire clip faces away from the blade, but in general the action shown in Fig. 4, is to be preferred, both on the ground of simplicity and economy of construction.

The length of the blade 13, being relatively long in comparison with the other dimensions will result in small motion of the clip and blade being possible without inducing any material operating strains and the bosses 22, 22 allow a correspondingly small rotational angle of clip faces allowing them to adhere to the blade during the initial motion. After passing beyond the limit thereof these clip

face bosses 22, 22, will hit with a hammer blow on the spring clip 2, and tend hence to free the blade by torsion; but the preferable method of overcoming adhesion is by the actual pulling apart of the clip faces as shown in Fig. 4 and the hammer blow between faces 1, 1, and ends 12, 12 is hence greatly to be desired.

While the construction shown in Figs. 1 to 4, comprises a clip external to the blade, an alternative construction may be used such as shown in Figs. 5, 6, 7 and 8, wherein 25 takes the place of the clip, consisting of a central member on which the bifurcated ends of blade 13 make external contact. 26, is a stationary member mounted rigidly on base 9, and is provided with an oval shaped projection 27, which is slightly wider at its widest point than clip 25.

The action is as follows:

When the blade end is moved upward in opening the two ends of blade 13 will impinge with a hammer blow upon piece 27 which will separate them, thus positively withdrawing them from the clip when breaking the frictional hold. The construction is quite parallel to that shown in the first four figures, and in general includes merely an external, instead of an internal blade, the other features of design being identical.

Figs. 9, 10, 11 and 12 show a modified form of construction similar in principle to that shown in Figs. 1 to 4, wherein piece 11, instead of being solidly mounted, is mounted on pivot 28, set in lugs 29, rigidly attached to base 9. A spring 30, tends to keep the piece 11 in the position shown. This piece is set in a slot 31, in casing 6.

When the blade end moves upward and carries the clip and casing 6, the righthand edge of slot 31 moves over the inclined portion of piece 11, causing this piece to go forward and the tyne 12, 12, will then strike the clip faces 1, 1, and cause the liberation of the clip in the manner shown in Fig. 4.

Figs. 13 and 14, show an alternative method of operation wherein the blade 13, is provided with a blade end 31, pivoted on pivot 32. Blade 13 is provided with limit bosses 33 and 34, which limit the rotation of the blade end. 35 is a shunt for carrying the current between blade 13 and blade end 31.

In closing the switch the resistance of the clip is such that blade end 31, is forced in by projection 33, of blade 13, and in opening the blade end is free to move thru a slight angular motion until boss 34 impinges on blade end 31. In the meantime the blade end 31, has assumed such a position that it will impinge on projections 36, 36, of clip faces 1, 1, and will tend to liberate the clip faces from the clip in the same manner as in the construction shown in Fig. 4.

The novel features of this invention consist in the fact that the motion of the blade

ends cause a positive breaking of the frictional contact between clip and blade other than that caused by the direct withdrawal from the blade. In other words, the initial motion in opening is such as to provide definite means of breaking directly this friction hold and separating the surfaces in contact by a direct pull preferably in a direction transverse to the plane of contact. Also the effect of inertia caused by slight motion is 10 made of avail in giving a hammer blow to effect the same result and cause the liberation of the blade.

What I claim is:

1. In an electric switch a blade, a clip contacting with said blade for carrying current therefrom, in combination with means for allowing an initial motion of said blade and said clip without substantial change of contact surfaces, and means actuated by the 15 initial motion of said blade and said clip for reducing the pressure between said blade and said clip, thereby effecting the ready release of said clip.
2. In an electric switch a blade, a clip for 20 contacting with said blade for carrying current therefrom and means for allowing a small free motion of both said blade and said clip on the initial movement of opening said switch, in combination with means for releasing the contact between said blade and said clip thru a hammer blow tending to separate transversely the contact faces of said clip and blade at the end of said movement.
3. In an electric switch a blade, a clip engaging said blade for carrying current therefrom, a movable member on which said clip is mounted, a second member adapted to diminish the contact pressure between said clip and said blade thru the motion of said 35 clip and said movable member.
4. In an electric switch a blade, a clip engaging said blade for carrying current therefrom, a movable pivoted member on which 40 said clip is mounted, a second member adapted to diminish the contact pressure between said clip and said blade upon the motion of said clip and said movable member, and thereby effect the ready liberation of said 45 blade from said clip.
5. In an electric switch a blade, a clip contacting with said blade for carrying current therefrom, an insulating support on which 50 said clip is movably mounted, and means for causing said clip to effect the ready liberation of said blade from said clip thru the reduction of pressure between the contacts of said blade and said clip.
6. In an electric switch, a blade, a clip 55 comprising contact faces for contacting with said blade, a supporting member in which said contact faces are pivotally mounted the axis of said pivot mounting being transverse to and passing through said faces when in 60 contact with the blade, a stop for limiting

the rotational motion of said faces said stop being adapted to effect thereby the ready liberation of said blade from said clip, a carriage on which said clip is mounted adapted to provide an initial motion on starting 70 to open the switch such that the relative positions of said clip faces and said blade will not be materially altered until said clip faces impinge on said stop for limiting the rotation thereof.

In testimony whereof, I affix my signature.
AUGUSTUS JESSE BOWIE.
